UNITED STATES PATENT OFFICE.

GEORG SCHMIDT, OF REINICKENDORF-OST, AND CARL BÖKER, OF BERLIN, GERMANY,
ASSIGNORS TO BAYERISCHE VEREINSBANK, OF MUNICH, GERMANY.

ELECTRIC ALARM APPARATUS.

Application filed May 6, 1921. Serial No. 487,277.

To all whom it may concern:

Be it known that we, GEORG SCHMIDT and CARL BÖKER, both citizens of the German Republic, residing at the 1st, Reinickendorf-
5 Ost, the 2nd, Berlin, Germany, have invented certain new and useful Improvements in Electric Alarm Apparatus, of which the following is a specification.

This invention relates to an alarm and 10 signaling apparatus designed to protect against burglary and fire. In an apparatus of this character, as is well known, two selenium cells or two similarly acting electric light cells are employed in connection 15 with a Wheatstone bridge. Devices of this construction have the selenium cell, together with the storage battery and the relay employed in connection therewith usually connected in series and upon the device operating 20 the current resulting for operating the device is of a low intensity. Furthermore, in the selenium apparatus of this character the same will operate to give an alarm upon the slightest increase of the surrounding 25 temperature. The relay employed must be very finely adjusted in order to signal a feeble gleam of light. The release of the alarm circuit is effected either by exposure or by shading, or by exposure and shading 30 of one or several selenium cells. According to this invention the arrangement has been made, that a working cell and a compensating cell are compensated by two resistances in a Wheatstone bridge in such a 35 manner that the relay in the bridge is currentless. Thus it is ensured that the relay acts only upon the electric light current and that the signalling device signals even a very feeble gleam of light. The inertia and the 40 inconstancy of the working cells are overcome further by the connection which has been just described. The alarm may be given according to this invention by a feeble gleam of light.

45 In order that the invention may be clearly understood, we will hereafter describe the same with reference to the form of construction which is diagrammatically shown by way of example in the accompanying drawing, wherein:—

W¹ and W² are two selenium cells. W¹ is enclosed in the case or box H which excludes all light; W² is situated behind an indicator disk drop K which closes a win-

dow tightly and is adapted to be swung 55 sideways and away from the window by the action of magnet M¹. W³ and W⁴ are the compensating resistances. In the Wheatstone bridge the relay R is arranged which is designed to close the alarm circuit by means of the hand Z and the adjustable contacts K¹, K². FS is a fuse for feeble currents and will fuse when the leads 2, 4 are bridged over, provoking thus the alarm signal. The multiple point switch Sch serves 65 to cut in the alarm apparatus. M_s is a maximum switch designed to short circuit the contact of the relay when the said relay has been operated, so that the relay is protected against over loading. L is an 70 optical signal and G is an acoustic signal. The battery B supplies the required energy.

The operation is as follows:—

When the device has to be switched on, the room to be protected has to be darkened, 75 whereupon the switch Sch is turned so that the switch lever P is in contact with II.

The circuit is now as follows:—

From the positive pole of the battery through lead 3, switch lever P, contact II, 80 lead 3^a, lead 4, screw D, spring F, armature A, wire C, winding of magnet M¹, lead 2^a and back through leads 2, 1 to the negative pole of the battery B. Owing to this circuit the armature A is attracted by the electro- 85 magnet M¹ and the disk K drops away from the selenium cell W². The spring F is thus moved away from contact screw D so that the current supply to the winding of magnet M¹ is interrupted. The switch Sch is 90 now moved to its operative position that is to say the switch lever P is placed upon the contacts III, IV.

The closed circuit current flows as follows:—

From the positive pole of the battery B, through lead 3, switch lever P, contact III, lead 3^b and is then divided, a part thereof flowing through fuse FS, lead 4, selenium cell W² to selenium cell W¹, lead 2, and the 100 remainder through lead 4, resistances W⁴, W³ and lead 1 back to the negative pole of the battery B. In the bridge of these connections the relay R is inserted between the leads 5 and 5^a.

The open current circuit is as follows:—

From the positive pole of battery B through lead 3, switch lever P, contact IV,

- lead 3^a, through bell G, lamp L, lead 1, through the winding of the maximum switch MS interposed in, lead 1 to the adjustable contacts K¹, K² and further from the negative pole of battery B over lead 1 to the contact pointer Z.
- The short-circuiting device X, Y of the maximum switch MS is connected by the leads 1 and 1^a with the contacts k¹, k² and 10 by the leads 1^a with the pointer Z. The plant is thus switched in ready for work. If now a light ray penetrates into the protected rooms in which the case with the selenium cells W¹, W² is situated, either 15 from a lighted match, or from a lighted pocket lantern, the resistance of the selenium cell W² decreases almost instantaneously and the electric proportion which was established in the working position is disturbed. Current will consequently flow 20 through the bridge so that the hand of relay R comes in contact with k² and the alarm device is operated. The current of the working circuit flows as follows:—
- 25 From the positive pole of battery B to 3, P, IV, 3^c, G—L, 1, M_s, 1, k², Z, 1 to the negative pole of battery B. Owing to the closing of the circuit the armature Y of the maximum switch is attracted and comes 30 in contact with screw X so that the contacts k², k¹, Z of the relay R are bridged over by means of leads 1, 1^a and the relay is released from the current. When the 35 closed current circuit is cut or when the leads 5—4, 5—2 are bridged over, the signal is given in the same manner. When the leads 2—4 are directly short-circuited the alarm is operated by the fusing of the fuse FS.
- 40 When the apparatus is to be cut out the contact lever P is brought in contact with I so that the disk K is placed over the selen-
- ium cell W² by the action of the magnet M².
- The circuit is as follows:—
- Positive pole of battery B, lead 3, P, I, 45 3^a through the winding of magnet M², lead 2^a, over leads 2, 1 back to the negative pole of B. Owing to the closing of this circuit the armature A is attracted by the magnet M², the spring F is again brought in contact with screw B and the disk K is placed 50 in front of the selenium cell W² so that this cell is shut off light-tightly. The switch Sch is now brought back to its initial O 55 position. By this turning of the switch the apparatus is cut out. Fire is signalled in the same manner.
- We claim:—
1. A device of the class described comprising a Wheatstone bridge, means for giving an alarm when said bridge becomes unbalanced, a pair of selenium cells in different legs of said bridge, whereby said bridge will remain balanced under varying temperature conditions, and a light excluding enclosure for one of the cells.
2. In an apparatus of the character described, a Wheatstone bridge, means for giving an alarm when said bridge becomes unbalanced, light responsive resistances inserted in the legs of the bridge, proportioned to maintain the bridge balanced under varying temperature conditions and also adapted to unbalance the bridge upon light falling upon either of said resistances.
- In testimony whereof we affix our signatures in presence of two witnesses.

GEORG SCHMIDT.
CARL BÖKER.
